UNITED STATES PATENT OFFICE.

CARL ANDREAS VIKTOR HALLGREN, OF STOCKHOLM, SWEDEN.

ROLLER FOR ROUND-PICKING GRINDSTONES, EMERY-WHEELS, &c.

SPECIFICATION forming part of Letters Patent No. 643,128, dated February 13, 1900.

Application filed April 22, 1899. Serial No. 714,076. (No model.)

To all whom it may concern:

Be it known that I, CARL ANDREAS VIKTOR HALLGREN, foreman, a subject of the King of Sweden and Norway, and a resident of Gref-
5 magnigatan 9, Stockholm, Sweden, have in-
vented certain new and useful Improvements in Rollers for Round-Picking of Grindstones, Emery-Wheels, and the Like or for Working Hard Surfaces in General, of which the fol-
10 lowing is a specification, reference being had therein to the accompanying drawings.

This invention relates to a roller for the round-picking of grindstones, emery-wheels, and the like or for working hard surfaces in general. It is composed of a number of small hard-steel rods radiating from the roller-shaft and bearing with their inner ends perpendicularly on the latter. By the aid of suitable intermediate collars the rods are held together
15 on the said shaft between a shoulder on the latter and some form of clamping-nut. The thickness of metal of the rods is but slight; but owing to their having a curved or corrugated cross-section the rods can without bending penetrate into the stone or surface with their free ends and without requiring at any time to be ground. The roller revolves freely
20 in a suitable holder, being driven by the rotating stone or emery-wheel or the surface in motion, in contact with which it is held, its
25 action being based on the aforesaid penetrative power of the rods. The work performed consequently consists in a rapid picking, the more intense as the diameter of the roller is
30 small in comparison with the grindstone or emery-wheel and its velocity of rotation con-
sequently quite great.

Figure 1 shows a section axially through the roller, and Fig. 2 an end view of same, par-
40 tially in section. Figs. 3 and 4 show a modified arrangement of the roller, and Figs. 5, 6,
45 and 7 the holder.

The small steel rods are designated by *a* and the shaft by *b*. The latter, which is tu-
50 bular in order that the roller may be slid onto the pin *g'* of the holder, Fig. 6, has a head *b'*, between which and the clamping-nuts *f* is clamped the collection of rods and distance-collars, the latter alternately consisting of
55 plate metal and some soft material—for in-
stance, pasteboard or leather. In putting the

tool together the shaft *b* is placed upright and a plate washer *c* is slid over it, a layer of rods *a* being subsequently placed on the latter. Then a paper disk *d* and a plate collar 55 *c* is put on and on the latter a fresh layer of rods, and so on. The whole is clamped together by means of the nuts *f*. The inner slightly-compressed ends of the rods are made to bear against the shaft of the roller, and the 60 rods are so placed that the side having sharp edges, owing to the corrugated or **U**-shaped cross-section of the rod, will face the pasteboard disk *d*. When the pieces are clamped together, the said edges enter into the paste- 65 board disk, and the whole is consequently fastened securely together. Only about half the length of the rods is embraced by the intermediate collars or distance-pieces, their free outer ends being enabled to enter in the 70 piece operated on until the roller has worn off close to the said collars. The wear is insig-
75 nificant, however, owing to the comparatively great length of the cutting edge, due to the curved or corrugated cross-section of the rod. Evidently this may differ from that shown in the drawings, being instead made **W** or **S** shaped, for instance.

The modified arrangement, Figs. 3 and 4, consists in that the rods are wound with wire, 80 which may be necessary when they are straight in cross-section—*i. e.*, when the latter is not curved or corrugated. The wind-
85 ing is done in the manner that each respec-
tive layer of rods is provided with a wire *g*, passing zigzag around the rods and coiled about the roller, so that only the outer ends of the rods are left free. In this manner each layer of rods forms a coherent disk, Fig. 4. This disk is dipped in melting tin or the like 90 even with the inner edge of the winding, so that the wire coils and the rods become soldered together. Several disks are subse-
95 quently slid onto the shaft, alternating with distance-pieces, and clamped together by means of the nuts, Fig. 3. The roller is used until the rods have worn down to the wind-
100 ing, a portion of the latter being afterward unraveled, as required. The winding may also be produced by passing the wire *g* back and forth along the axis of the roller around the rows of rods.

The roller is inserted in the fork *h* of the holder, Figs. 5 to 7, being allowed to revolve freely on the pin *g*' of said fork. The holder, moreover, consists of the support *i*, carrying the fork *h*, the sleeve *k*, which can be moved along the frame *l* by means of the screw *n*, and the screw *m*, belonging to the support and surrounded by the sleeve *k*, and with which screw engages the nut *p*, which is rotatably attached to the sleeve and serves for moving the roller-support backward or forward at right angles to the frame *l*. The fork *h* has a pivot-pin *r* passing up through the support *i* and provided with a tightening-nut *s*. The holder is attached in such a manner to the grindstone or emery-wheel frame that the roller can be moved in contact with the stone or wheel, (indicated by the arc *v*.) If it is desired to turn off the edge of the stone or wheel, the roller is adjusted accordingly by turning the fork on the pin *r*.

Having now described my invention, what I claim as new, and desire to secure by Letters Patent, is—

25 1. A cutter or dressing-tool consisting of a series of rings each comprising a plurality of radially-arranged rods with means for holding said rods together with their outer ends spaced apart, the said rods being of channel 30 cross-section form, said radial rods being in-

dependent of each other, substantially as described.

2. A cutter or dressing-tool consisting of a shaft, a series of rings each comprising a plurality of independent channelled rods, means 35 for holding the rods of each ring together, and means for clamping the several rings to each other and upon said shaft, substantially as described.

3. In combination, the series of rods radially arranged with spaces between them, wires intertwined with said rods for holding them together, the shaft *b* for holding the rods and means for holding the rods on said shaft, substantially as described. 40

4. In combination, the shaft, the series of rods radially arranged with spaces between them and wires intertwined with said rods for holding them together, said wires and rods being soldered together and means for clamping the rods on said shaft, substantially as described. 45

In witness whereof I have hereunto signed my name in the presence of two subscribing witnesses.

CARL ANDREAS VIKTOR HALLGREN.

Witnesses:

HANS B. OHESSON,
J. F. A. RUTBÄCK.

It is hereby certified that the name of the patentee in Letters Patent No. 643,128, granted February 13, 1900, for an improvement in "Rollers for Round-Picking Grindstones, Emery-Wheels," &c., was erroneously written and printed "Carl Andreas Viktor Hallgren," whereas said name should have been written and printed *Carl Andreas Viktor Hällgren*; and that the said Letters Patent should be read with this correction therein that the same may conform to the record of the case in the Patent Office.

Signed, countersigned, and sealed this 24th day of April, A. D., 1900.

[SEAL.]

THOS. RYAN,

First Assistant Secretary of the Interior.
